Attorney

UNITED STATES PATENT OFFICE.

ALEXANDER RICE, OF MONTGOMERY, ALABAMA.

DESIGN FOR A NOVELTY PAPER HAT.

52,147.

Specification for Design.

Patented July 2, 1918.

Application filed March 16, 1918. Serial No. 222,971. Term of patent 3½ years.

To all whom it may concern:

Be it known that I, ALEXANDER RICE, a citizen of the United States, residing at Montgomery, in the county of Montgomery and State of Alabama, have invented a new, original, and ornamental Design for Novelty Paper Hats, of which the following is a specification, reference being had to the accompanying drawing, forming part of the same.

The figure is a perspective view of a novelty paper hat, showing my new design.

I claim:

The ornamental design for a novelty paper hat, as shown.

ALEXANDER RICE.

Witnesses:

THEO. L. MEYER,
J. E. HYDE.
